UNITED STATES PATENT OFFICE.

CHARLES E. BELL, OF CHICAGO, ILLINOIS.

PROTECTING DEVICE.

Application filed March 8, 1922. Serial No. 542,031.

To all whom it may concern:

Be it known that I, CHARLES E. BELL, a citizen of the United States, residing at Chicago, in the county of Cook and State 5 of Illinois, have invented a new and useful Improvement in Protecting Devices, of which the following is a specification.

This invention relates to improvements in protecting devices, and more especially to a 10 protecting device especially adapted for use in connection with vault doors, safe doors and the like, to protect the same against unauthorized opening or breaking. My invention will be fully understood by reference to 15 the following specification and accompanying drawings, in which I have shown a form of device embodying the features of my invention.

As shown in the drawings, Figure 1 is a 20 view in front elevation of my improved protecting device, showing the same in place on the front of a vault door, Fig. 2 is a view taken as indicated by the line 2 of Fig. 1, Fig. 3 is a view taken as indicated by the line 25 3 of Fig. 2, Fig. 4 is a view taken as indicated by the line 4 of Fig. 1, Fig. 5 is a view taken as indicated by the line 5 of Fig. 1, Fig. 6 is a view taken as indicated by the line 6 of Fig. 1, 30 showing a part broken away, Fig. 7 is a view taken as indicated by the line 7 of Fig. 3, and Fig. 8 is a view taken as indicated by the line 8 of Fig. 3.

As shown in the drawings, 20 indicates 35 the door of a vault, and 21 the jamb member at the side. Mounted on the door 20 is a tapering box-like casing held in place by the machine-screws 23, the heads of which engage with the keyhole slots 24 in the back 40 face of the casing 22. The casing 22 is provided with a longitudinal slot 25 on its back face arranged in the center, and extending the entire length of the casing and about half-way into the end face 22^a (adjacent the jamb) thereof. Mounted within 45 the casing 22, at about the center, is a plate 26 provided with a tongue 27 extending into the slot 25. The plate 26 is about one-half of the cross-sectional area of the interior of 50 the casing 22 and is located adjacent the back wall thereof. This plate is placed about midway between the two ends of the casing 22. Mounted in the casing 22 and adapted for endwise sliding movement therein is a bolt 55 29, having its end lying toward the jamb enlarged, and its other end made smaller in

diameter, as indicated by 29^a. The enlarged end of the bolt 29 extends through the slot 25 in the end face 22^a of the casing 22, and its other end projects through a hole 30 in the opposite end face of the casing 22. The smaller end of the bolt 29 is provided with a hand knob 31 and an annular groove 32 is provided near its other end. The bolt part 29^a passes through a hole 33 in the plate 26. 60 65

Near the larger end of the casing 22 is slidably mounted a plate 35 between four rods 36, as shown. The plate 35 is adapted for transverse sliding movement within the casing 22, the rods 36 serving as guides. The plate 35 is provided with a hole 37 adapted to accommodate the bolt 29, and also provided with three vertically arranged holes 38 near its front edge, adapted to accommodate the ends of three glass tubes 39, which are parallelly arranged within the casing 22 and extend substantially its entire length, so arranged that they lie at about their middle points against the forward edge of the plate 26. The space within the casing 22 between the plate 26 and its smaller end, is filled with suitable cementitious material 40, such as plaster of Paris, within which about half of each glass tube 39 is imbedded. A tube 41 is provided within this cementitious material to accommodate the part 29^a of the bolt 29 and permit sliding movement of the same therethrough. When the parts are arranged in their normal position, the plate 35 is in its forward position in the casing 22 (see Fig. 4), and the glass tubes 39 lie against the forward edge of the plate 26 (see Fig. 5). The part 29^a of the bolt fits loosely in the hole 33 in the plate 26. When so arranged, it is obvious that relative movement of the enlarged end of the bolt 29 in the slot 25 toward the door 20 serves to slide the plate 35 between the rods 36 toward the door. This movement of the plate 35 pulls the ends of the glass tubes 39 toward the door, thus operating to break these tubes over the forward edge of the plate 26, since their other ends are firmly imbedded in the plaster of Paris 40. This breakage of the tubes 39 permits their liquid contents 45 to run therefrom and mix and escape through perforations 46 in the lower surface of the casing 22. 70 75 80 85

I will now describe the means provided for causing relative movement of the enlarged end of the bolt 29 toward the door 20, when the vault door is opened for the 90 95 100 105 110

I will now describe the means provided for causing relative movement of the enlarged end of the bolt 29 toward the door 20, when the vault door is opened for the

purpose of breaking the glass tubes, as described above. In general, it might be stated that there is mounted on the jamb 21 a socket member provided with a hole or socket 50, adapted to accommodate the enlarged end of the bolt 29. Locking means are also provided for preventing withdrawal of the bolt. This socket member comprises a block 51 suitably mounted on the jamb 21, 10 by means of machine screws 52, the heads 53 of which are located within suitable recesses 54 and engaged by the shoulders 35^a. The block 51, on its face adjacent the end of the casing 22, is provided with an in-set 15 plate 61 held in position by the screws 62. When this plate 61 is in place, the heads 53 of the machine screws 52 are firmly gripped, thus holding the block 51 and plate 61 firmly in position on the jamb 21. When 20 the vault door is closed, the heads of the screws 62 are covered by the end 22^a of the casing 22. The socket or hole 50 extends through the plate 61 and into the block 51 and is adapted to receive the end of the bolt 29 when the vault door is closed. In 25 operation, the bolt 29 is slid to the right (as viewed in Fig. 2) to the position indicated by the broken lines. The door is then closed, and the bolt is then slid to the left, 30 so that its end enters the socket 50. When in this position, it is obvious that, if the vault door be opened, the end of the bolt 29 will be held stationary while the door is moved outwardly, thus causing relative 35 movement of the bolt 29 toward the door, to slide the plate 35, to move the ends of the tubes 39 and break the same over the forward edge of the plate 26, as described above.

40 The following means are provided for locking the bolt 29 within the socket 50 to prevent unauthorized removal of the same therefrom. Mounted on the face of the plate 61, adjacent the block 51, is a vertically slidable bolt 80, with its lower end forked as indicated by 81 and adapted to engage with the groove 32 in the bolt 29.

45 The bolt 80 is adapted for upward or downward sliding movement, and any suitable locking means, as indicated in general by 83, are provided for locking the same in its lowermost position. The locking means 83 are adapted to be controlled by a key 85, and a projection 86 is provided on the upper surface of the casing 22 opposite the lock 83 (when the door is closed), in order to prevent or obstruct the use of a 50 drill or other tool against the lock 83, for the purpose of unauthorized tampering. In 55 operation, the bolt 29 is slid into the socket 50 after the door is closed, and the bolt 80 is then turned to its lowermost position and locked by means of the key 85, thus bringing the forked end 81 of the bolt 80 60 into engagement with the groove 32, thus

preventing the bolt 29 from being slid out of the hole 50.

Suitable means are provided for showing whether the device is locked or set. Slidably mounted on the smaller end of the casing 22 is a plate 90, provided with a rectangular opening 91. This plate is bent around over the end of the casing and provided with a hole through which the rod 29^a passes. The knob 31 is attached to this part of the plate in any suitable manner; so that sliding movement of the bolt serves to slide the plate 90. When the bolt 29 is in the socket 50, the opening 91 in the plate 90 registers with and discloses a red rectangle 93 on the front of the casing 22. When the bolt is pulled out of the hole 50 to the position indicated by the dotted lines in Fig. 2, this red patch 93 is covered. Therefore, when red shows the bolt is in place, or the device is locked or set.

Within the casing 22, in front of the tubes 39, are provided strips 100 of hardened metal to prevent and hinder tampering or cutting. Likewise hardened metal 101 surrounds the hole 50. Similarly hardened metal 102 is placed in the projection 86. The enlarged part 29 of the bolt is hollowed, as indicated by 104 (see Fig. 7). This hollow part may be filled with any suitable explosive, so that any tampering with the bolt or cutting of the same will cause an explosion which will break the tubes 39.

It will be noted from the foregoing description that the principal object is to break the glass tubes 39 and empty the contents therefrom. These glass tubes are adapted to contain liquids, which singly, or upon mixing, give off poisonous or irritating gases or fumes which will cause any one tampering with the vault to leave the vicinity. Any suitable liquid or liquids may be used in these tubes. For example, one tube may contain chloropicrin, another tube stannic chlorid, and the third tube ammonium hydroxid saturated with ammonium chlorid and when these three liquids mix, heat is generated which vaporizes the chloropicrin and causes it to give off irritating vapors and fumes. The chloropicrin alone, upon being released from the tube, will vaporize and give off noxious and irritating gases and fumes.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as possible in view of the prior art.

What I claim as new and desire to secure by Letters Patent, is:

1. In combination with a door and jamb, a casing on the door, a plurality of separate frangible tubes within the casing each containing a noxious gas producing liquid, a part movably mounted within the casing and adapted to bear against the frangible tubes, and a rod engaging said movably mounted part and projecting from the casing and engaged by a part on the jamb, whereby relative movement between the door and the jamb will move said rod to cause said movably mounted part within the casing to press against the frangible tubes to break the same. 5
- 10 2. In combination with door and jamb members, a casing mounted on one of said members, a frangible tube within the casing containing a noxious gas producing liquid, a part movably mounted within the casing and bearing against the frangible tube, and means actuated by relative movement between the door and jamb members to press said movably mounted part against said tube to break the same. 15
- 15 3. In combination with door and jamb members, a casing mounted on one of said members, a frangible tube within the casing containing a noxious gas producing liquid, a part movably mounted within the casing and adapted to bear against the frangible tube, and a rod engaging said movably 20
- 20 4. In combination with door and jamb members, a frangible tube containing a noxious gas producing liquid supported on one of said members, a part movably mounted on said member with respect to said frangible tube and bearing against said frangible tube, and means actuated by relative movement between the door and jamb members to 25 press said movably mounted part against said tube to break the same. 35
- 25 5. In combination with door and jamb members, a frangible tube containing a noxious gas producing liquid mounted upon one of said members, a part movably mounted with respect to said frangible tube, and means actuated by relative movement between the door and jamb members to press said movably mounted part against said 30 40 45 50 55 frangible tube to break the same. 55

Witness my hand and seal this 20 day of February, 1922.

CHARLES E. BELL. [L. S.]
